UNITED STATES PATENT OFFICE.

LUTHER C. CROWELL, OF BROOKLYN, ASSIGNOR, BY DIRECT AND MESNE ASSIGNMENTS, TO ROBERT HOE, STEPHEN D. TUCKER, THEODORE H. MEAD, AND CHARLES W. CARPENTER, OF NEW YORK, N. Y.

DELIVERY MECHANISM FOR WEB-PRINTING MACHINES.

SPECIFICATION forming part of Letters Patent No. 453,407, dated June 2, 1891.

Application filed March 28, 1890. Serial No. 345,737. (No model.)

To all whom it may concern:

Be it known that I, LUTHER C. CROWELL, a citizen of the United States, residing at Brooklyn, county of Kings, and State of New York, have invented certain new and useful Improvements in Delivery Mechanism for Web-Printing Machines, fully described and represented in the following specification and the accompanying drawings, forming a part of the same.

This invention relates to improvements in delivery mechanism for web-printing machines, especially of the class capacitated to print and deliver products varying in the number of pages or number of folds imparted to the sheet.

It is one of the objects of the present invention to provide in compact form a combined newspaper and pamphlet printing press which shall be capacitated to produce a large variety of products varying from newspaper size to that of a small pamphlet, and in which the changes necessary for varying the products shall consist of a slight and convenient adjustment of parts.

With this object in view one part of my invention consists, generally, in the combination, with a suitable printing mechanism and cutting, collecting, and folding cylinders, of folding and delivery mechanism, whereby one or more additional transverse folds may be imparted to the sheet after passing the cutting, collecting, and folding cylinders, and whereby an additional longitudinal fold may be imparted to the sheet, the latter being delivered to one or the other of two flies and sets of carrier tapes, the folding and delivery mechanism being so constructed that the use of switches is entirely avoided, and the various products are obtained by a simple adjustment of one or more parts of the operating mechanism.

Another object of my invention is to improve the general construction of delivery mechanism for web-printing machines; and to this end my invention consists, further, of various improvements of general application in this class of mechanism, whereby the construction is greatly simplified, its operation rendered more certain and reliable, and a

more accurate registry of the sheet secured, all of which will be more particularly described in the specification and pointed out in the claims.

A full description of the invention will now be given, reference being had to the accompanying drawings, forming a part of this specification, in which—

Figure 1 is a side elevation of a web-printing machine embodying my improvements. Fig. 2 is a side elevation of the printing end of the machine on a larger scale than Fig. 1. Fig. 3 is a side elevation of the delivery end of the machine on the same scale as Fig. 2. Fig. 4 is a view similar to Fig. 3, taken on the opposite side of the machine. Fig. 5 is a cross-section on the line 5 of Figs. 3 and 4, showing the web-turner. Fig. 6 is a plan view of the delivery end of the machine, certain parts being removed. Fig. 7 is an end view of the delivery mechanism. Fig. 8 is a diagrammatic sectional elevation showing the course of the sheet from the cutting and collecting cylinders. Fig. 9 is an end view of the transverse folding mechanism of the machine, taken inside the frame. Fig. 10 is a detail sectional elevation of the collecting and folding cylinder and its mechanism. Fig. 11 is a detail which will be hereinafter referred to. Fig. 12 is an end view of one of the folding-rolls and its folding mechanism. Fig. 13 is a detail side view of the same. Fig. 14 is a plan of the same. Fig. 15 is a cross-section of the cutting, collecting, and folding cylinders, showing the operation of the tucking-blade and guards and the deflecting-guide. Fig. 16 is a plan view of the same. Fig. 17 is a sectional elevation showing the deflecting-guide and the means for mounting and adjusting the same. Fig. 18 is a detail side view of the same. Fig. 19 shows a modified form of the same. Fig. 20 is a cross-section of the guide. Fig. 21 is a detail section on line 21 21 of Fig. 5. Fig. 22 is a detail of the means for locking the folding-roll gears in position. Fig. 23 is a detail of the arm for operating the longitudinal folding-blade. Fig. 24 is a detail of the mechanism for slitting the edge of the sheet prior to folding. Figs. 25 and 26 show products.

Referring now especially to Figs. 1 to 5, it will be understood that the printing mechanism may be of any ordinary construction, that shown consisting, essentially, of the type-cylinder A and impression-cylinder B, the two forming, together with the web-turner C, a printing and perfecting mechanism similar to that described and claimed in my Letters Patent No. 212,444. The type-cylinder A may be furnished with an inking mechanism of any suitable form, that shown consisting, essentially, of the distributing-cylinder D, distributing-rolls d, form-rolls e, and the usual fountain and transfer rolls. For imparting the necessary movements for feeding and distributing the ink upon the cylinder D any of the common forms of mechanism may be used. I prefer to employ that shown, which, however, forms no part of the present invention, but is described and claimed in my prior application, Serial No. 274,032, filed May 16, 1888, and need be but briefly described herein.

The distributing-cylinder D is mounted to reciprocate in its bearings, this reciprocating motion being imparted to it by the lever 10, provided with a bowl engaging with a pulley on the shaft of the distributing-cylinder, this lever 10 being pivoted on the frame and operated by means of an eccentric stud on a short shaft 12, which carries a worm-wheel 13, actuated by a worm-gear 14 on a short shaft 15, which is operated from the shaft of the distributing-cylinder by suitable gears. (Not shown.) The transfer-roll 16 is carried against the fountain-roller by means of a cam 17 on the shaft 12, which operates against a bowl 16, carried on the end of one of the arms 18, supporting the transfer-roll, the latter being returned by its weight or by suitable springs. The fountain-roll is provided with the usual pawl-and-ratchet mechanism for rotating it, the lever 19, carrying the pawl, being actuated through the connecting-rod 20, adjustably connected to a lever 21, which is operated at each vibration of the lever 10 through suitable geared segments (not shown) carried, respectively, by the levers 10 and 21. A lever 22, carrying a bowl engaging with the pulley 11 on the shaft of the distributing-cylinder, reciprocates one of the form-rolls d in the direction opposite to the movement of the distributing-cylinder. The web E is led from a web-roll at the end of the machine, which is provided with the usual brake and tension devices 8 9, and passes thence to the control of the first series of tapes a b. The upper series of tapes a, as shown in Fig. 1, pass under the conducting-rolls 23 and upward past the impression-cylinder B, returning round another conducting-roll 23 and tightening-pulleys 24 to the first roll. The under series of tapes b pass over the conducting-rolls 25 and around tightening-pulleys 26.

The operation of the printing mechanism and the movement of the web after it leaves the control of the tapes a b is the same as in my prior patent, No. 212,444, above referred

to, and need not be described here further than to say that the web passes between the type and impression cylinders A B at one end, 70 where it is printed upon one side, thence over one end of the two-part conducting-roll 27, downward around the turner C, returning over the other side of the turner and the other end of the two-part conducting-roll 27, 75 as shown in Fig. 5, thence downward around the impression-cylinder B, and upward between the cylinders A B at the end opposite that by which the first impression was made, the web thus being perfected and passing 80 over the conducting-roll 28 to the delivery mechanism.

It will be understood that the two parts of the roll 27 are rotated in opposite directions by means of gears at either end of the machine, the movement of one part being reversed by a second intermediate, as shown clearly in dotted lines in Figs. 1 and 3 and in full lines in Fig. 4.

The operation of the web-turner is the same 90 as in my patent above referred to; but I have provided the following means of adjustment: The turner C is provided at its lower end with a fork 29, which embraces and slides on a short shaft 30, supported in the frame of 95 the machine, this construction preventing any swinging movement of the lower end of the turner. The turner is supported from the shaft 31 by forked arms 32 at each side of the machine, the arm 32 at one side being 100 provided with a downward extension, forming a bell-crank lever, as shown clearly in Fig. 21. The depending arm of this bell-crank is forked and engages a grooved nut 33, moving on a screw 33^a, provided with a 105 hand-wheel and supported in the frame, and which slides transversely of the machine in a slotted plate 34, attached thereto. The shaft 31 also slides transversely of the machine and is provided at one side with an arm 35, through 110 which a screw 36 passes into the frame, the screw 36 being provided with a hand-wheel for convenient operation. It will be seen that by rotating the screw 33 the horizontal arm 32 of the bell-crank lever will be thrown 115 upward, thus raising the turner C, and that an adjustment of the turner transversely of the machine is obtained by the movement of the screw 36, the turner being held in position vertically and longitudinally of the machine by the slotted plate 34 and the fork 29 and shaft 30, which, however, allow the transverse sliding movement. This mechanism for adjusting the web-turner is not claimed herein, but is covered by another application, 120 Serial No. 356,001, filed June 19, 1890.

Referring now particularly to Figs. 3, 4, 6, and 7, it will be seen that the web E passes from the roll 28 over the series of tapes f and is conveyed by them and the upper series of tapes g to the longitudinal folder F, from which the web passes between the usual external turning-rolls 51 and feeding-rolls 52 to the cutting, collecting, and folding mechanism.

The lower series of tapes *f*, as shown in Fig. 3, pass from the roll 28, just in advance of the printing mechanism, to the conducting-roll 37, thence backward around roll 38, forward 5 around tightening-pulleys 39, and returning thence to roll 28. The roll 28 is mounted in a fixed position in the main frame, while the conducting-roll 37, from which the tapes receive their motion the roll 38, and pulleys 39 10 are mounted in a frame sliding on the main frame, as will presently be described. The upper series of tapes *g* are carried by the sliding frame and pass around the tightening-pulleys 40, thence forward over the roll 37, re- 15 turning around the conducting-roll 41. A slitter 42 is carried by an arm upon the transverse shaft 43, which also supports the arms carrying pulleys 40. This shaft 43 is adjustable by means of the arm 44, provided with 20 a thumb-screw 45, as shown in Fig. 4, whereby the slitter may be secured in or out of operative position.

As shown in Figs. 4, 5, and 7, the frame *G*, sliding on the top of the main frame and carrying the feeding mechanism and slitter just described, is provided at either side of the machine with a rack-bar 46, engaged by gears 47 upon a transverse shaft 48, by which the frame may be moved in either direction, carrying 25 with it the folder and conducting rolls and tapes, the shaft 48 being provided with a square head outside the frame for rotating it. The frame *G* is provided with a downward extension 49, which carries an adjustable arm 50, provided with a support for the folder, as shown in Fig. 3.

The conducting rolls and slitter are driven by a system of gears shown in Fig. 4, and for the purpose of retaining the gears in mesh, 40 while allowing the movement of the frame *G*, the shaft of gear 3, carried by the frame and driving the rolls and slitter, has loosely mounted upon it a swinging arm 5, carrying the shaft of an intermediate 4, with which 45 gear 3 meshes. The shaft of gear 4 is mounted also in a second arm 6, swinging on the shaft of a gear 7, mounted in the main frame, and driving gear 3 through the intermediate 4. The intermediate 4 is thus supported in the 50 arms 5 6, and must, as the frame *G* moves, preserve its distance from both the driving and driven shafts and remain in mesh with the gears thereon. For steadyng the shaft of gear 3 a plate *h* is supported upon the end 55 of the frame *G* and slotted to receive the shaft, this plate having an adjustable connection with frame *G* by means of slots and bolts 1, Fig. 6. The frame *G* is similarly secured to the main frame by slots and bolts 2.

60 It will readily be understood that by loosening the bolts 2 and rotating the shaft 48, carrying the gears 47, the frame *G* may be moved forward and backward, carrying with it the folder *F* and the series of tapes, thus securing 65 accurate adjustment for the folder relatively to the cutting, collecting, and delivery mechanism, the swinging connection of

gears 3, 4, and 7 allowing the movement of the frame without throwing the gears out of mesh, as previously described. Upon tightening 70 the bolts 2 the frame will again be locked in position.

By reference to Fig. 3 it will be understood that the movement of the frame does not effect the tension of the lower series of tapes *f* 75 on account of the manner in which the tapes are led, as previously described, the forward or rearward movement of the conducting-roll 37, which tends to tighten or loosen the tapes, being compensated for by the equal forward 80 or rearward movement of roll 38, having the opposite effect upon the tapes. From the longitudinal folder *F* and the rolls 51 52 the web passes to the cutting, collecting, and folding cylinders, which will be now described. 85

Referring particularly to Figs. 9, 10, and 11, *H* *I* are the usual pair of cutting and collecting cylinders, each of a circumference equal to the length of a single sheet. The cylinder *I* is provided with the cutting-blade 53 and 90 the cylinder *H* with the groove 54 to receive the same. The cylinder *H* is provided also with the usual sheet-holding pins *c* or other suitable sheet-holding devices, which are carried by crank-arm 55, extending from the 95 supporting-shaft, and are normally held in operative position by means of the usual crank-arm 56, sliding rod 57, and spring 58.

It will be understood that any of the ordinary forms of folding-blades and mechanism 100 for operating the same and the sheet-folding devices may be employed in this machine. I prefer to use, however, the folding-blade and operating mechanism shown, which forms no part of the present invention, but is described 105 and claimed in my prior application, Serial No. 327,100, filed October 15, 1889, and need not be described in detail herein, the following general description sufficing.

The cylinder *H* is provided with a double-edged folding-blade *k*, which is mounted upon shaft 59, journaled in the heads of the cylinder and operated to fold the sheet or sheets carried by the cylinder into the bite of a pair of folding-rolls in the usual manner. The 110 shaft 59 is provided at one end with a transverse arm 60, parallel with the blade and carrying two operating-bowls 61 placed inside the edge of the blade. The arm 60 extends beyond the operating-bowls 61, and is provided 115 at its ends with heart-shaped projections 62, for a purpose presently to be described. Secured to the frame at the end of the cylinder *H* is a circular cam *K*, by which the bowls 61 of the arm 60 are operated, the 120 cam being so shaped that the folding-blade is held in position with neither of its edges protruded beyond the periphery of the cylinder, except just at the point where the folding- 125 rolls, where the cam is so shaped as to permit the folding-blade to make the required movement for folding the sheet. Within the exterior cam *K* and supported by the frame- 130

work of the machine is a plate L, which reciprocates vertically between guides 64, secured to the frame, the lower end of the plate being inclined in opposite directions, so as to 5 form a cam m, conforming in shape to the cam K at that point and forming the interior cam for operating the folding-blade when the plate L is in its raised position. In order to control the movement of the folding-blade at the 10 point of its greatest protrusion, which is just as the bowl 61 passes the point of the cam m, the cam K is provided with a pair of cam-surfaces 65, which project inward from its inner face, and between which passes the heart-shaped end 62 of the arm 60, the movement 15 of the blade thus being controlled until the bowl 61 has passed into the control of the cam m upon the opposite side of the folding-point. The movable plate L is provided, also, with an 20 inwardly-projecting shoulder forming a cam n, which, when the plate is in its lowest position, forms a continuation of the annular portion of the cam K, so that the advance bowl 61 upon the arm 60, instead of being directed 25 outward to fold the sheet, is continued onward in its annular path, the blade not being operated and no folding taking place. The upper end of the plate L is provided, also, with a cam o, which, when the plate is in its raised 30 position, engages a bowl 66 on a crank-arm extending from the shaft of the sheet-holding devices and retracts the pins c, so as to release the sheet or sheets in time to permit them to be folded by the blade k. It is evident 35 that when the plate L is in its lowest position the cam o will not operate to retract the pins. The plate L is slotted vertically to permit it to move over a box extending inward from the frame and supporting the shaft 67 of the cylinder H, as shown 40 in Figs. 9 and 10. For reciprocating the plate L the shaft 67 of the cylinder H is extended through the frame-work and has splined thereto a small gear 68, which may be 45 removed from the shaft and engages with a gear 69 of twice its size secured upon the end of a short shaft 70, which passes through the frame-work and is provided with a crank having a bowl 71, which enters an opening in 50 the plate L. The gear 69 being double the size of the gear 68, the crank makes one revolution to two revolutions of the cylinder H, and the plate L, with its cams, is raised upon one revolution of the cylinder and depressed 55 at the next, the movement being so timed that the plate will be in its respective raised and lowered positions at the time the folding-blade passes the folding-rolls. It is important that the cams m n should remain in a fixed 60 position during the time they are acting upon the bowls 61. To effect this, the opening p, in which the bowl 71 works, is provided with grooved recesses upon its opposite sides, in which the bowl 71 enters as the plate L reaches 65 the extreme limit of its movement in either

direction, thus holding the plate in fixed position during the operation of the cams m and n upon the bowls 61.

The operation of the parts is as follows: In folding, the edge of the blade which is in advance relatively to the rotation of the cylinder H as it arrives at the first of the folding-rolls is caused to move outward beyond the periphery of the cylinder by the cams m and K, and its movement is continued as the blade 70 passes the rolls, so that its edge is projected into the bite of two folding-rolls, thereby imparting a quarter-revolution to the blade, the heart-shaped projection 62 at the end of the arm passing between the fixed cams 65 and 80 controlling the movement of the arm and blade as the bowl passes the point of the cam m. As the movement of the cylinder continues the arm 60 and blade k are reversed, a half-revolution being completed by the action 85 of the other side of the cam m and the fixed cams 65. On the next revolution of the cylinder the other edge of the blade performs the folding, and the arm and the blade are reversed as before. In this case—that is, 90 when the folding-blade is to operate at each revolution and the sheets are not to be collected—the gear will be detached from the shaft 67, and the plate L will be moved to its raised position and secured therein in any suitable manner—as, for example, by a threaded bolt 72, which is passed through an opening in the gear 69 and the frame-work and enters a threaded opening in the plate L, as shown 95 in dotted lines in Fig. 10. The plate being 100 secured in this position, the cam o will operate to retract the pins at each revolution of the cylinder and the cam m will remain in position to direct the bowl 61 outward for the operation of the folding-blade. If the sheets 105 are to be collected, the folding-blade will be operated only at each alternate revolution of the cylinder. In this case the bolt 72 will be withdrawn and the gear 68 secured to the shaft 67, as in Fig. 10. As the blade 110 approaches the folding-rolls upon the first revolution the crank carrying the bowl 71 will be in position to depress the plate L, so that the advance bowl 61, instead of being operated by the cam m for folding, will be carried onward in its annular path by the cam n, and as a consequence no folding will take place, and, cam o being depressed, the pins c will not be retracted. Upon the second revolution of the cylinder the crank carrying the 115 bowl 71 will be in position to raise the plate L, so that the bowl 61 will be operated by the cam m and the pins c will be retracted by the cam o. This operation will be repeated, folding taking place at each alternate revolution 120 of the cylinder.

If for any reason it should be desired to render the folding-blade entirely inoperative, the plate L will be moved to its lower position, the gear 68 being removed, when the 125

weight of the plate will cause it to remain as positioned, or it may be secured thus in any suitable manner.

The mechanism of the cutting, collecting, 5 and folding cylinders thus far described is that of the application referred to.

For the purpose of guarding against the possibility of the machine being started while the gear 68 is fast to the shaft 67 and the 10 gear 69 and plate L fast to the frame, in which case it is evident that serious breakage would result, I provide the following improved device: The gear 68, as previously stated, may be splined upon the shaft 67 and a holding- 15 plate 74 secured to the gear by screws, as shown in Figs. 10 and 11, and provided with a central opening, through which a screw 75 passes to secure the plate and gear to the end of the shaft. The central opening in the 20 plate 74 is enlarged and screw-threaded, from which it will be seen that by removing the screw 75, which holds the plate to the shaft by pressure of its head upon the plate, an enlarged screw-threaded bolt may be inserted, 25 by turning which against the end of the shaft the plate 74 and gear 68 will be withdrawn. Sliding upon bolts 76 in the frame is a slotted safety-plate 77, provided with an opening 78, which in the raised position of the plate reg- 30isters with the opening in the gear-wheel 69, through which the threaded bolt 72 passes for securing the gear to the frame. The safety-plate 77 in its lowest position extends upward to the lower edge of the gear 68 and 35 in its upper position extends partially over the space occupied by the gear when in position, as shown clearly in Fig. 11. When the gear 68 and plate 74 are in position, the plate 77 is held from upward movement by the 40 plate 74, which extends outward into the path of movement of the safety-plate 77. It will readily be seen from this construction that it is impossible to raise the safety-plate 77, so as to insert the bolt 72, until the gear 68 and 45 plate 74 have been removed, and on the other hand it is impossible to introduce the gear 68 and plate 74 for securing it to the shaft until the bolt 72 has been removed to allow the safety-plate 77 to be lowered.

50 The supplementary transverse folding mechanism will now be described.

The sheet is folded from the cylinder H by the blade k between a pair of folding-rolls M N, the former carrying a single-edged folding-blade, by which the sheet at each alternate revolution is either folded or guided between the rolls N O, from which it passes under control of the tapes r over the guide 79, Fig. 8, and thence to a second pair of folding-rolls 55 P Q, the former of which carries a single-edged folding-blade similar to that of roll M, by which the sheet is folded or guided between the rolls Q R and passes thence under control of the tapes r s either directly to a fly 60 at the side of the machine or, after receiving a longitudinal fold, to a fly at the end of the machine, as will presently be described. The

construction and operation of the two pairs of folding-rolls M N and P Q being the same, a detailed description of one pair will be suf- 70

Referring particularly to Figs. 12, 13, and 14, the roll M, which is half the size of the cylinder H—that is, its circumference is equal to the length of the sheet folded once 75 transversely by the cutting and collecting cylinders—is provided with a single-edged folding-blade t, the shaft of which is provided with a transverse arm 80, carrying two bowls 81, located inside the edge of the blade and 80 the ends of the arm, the arm being provided at each end with a heart-shaped extension 82. At the end of the roll and secured to the frame is a cam S, the inner operating-surface of which is annular, except directly opposite 85 the point at which the sheet is to be folded between the rolls N O, at which point the cam is so formed as to permit the bowl 81 and the blade t to be carried forward, so that the blade will pass between the 90 rolls for folding or guiding the paper. The cam S is provided with an inwardly-extending flange 83, which extends into the plane of rotation of the arm 80 and bowl 81, and the operating part of which, as shown 95 clearly in Fig. 12, is formed with sides inclined in opposite directions to form a cam w, conforming generally in shape to the cam S at that point and constituting an interior cam operating on the bowl 81 to direct the 100 blade t between the rolls N O, the arm 80 being reversed as it passes the point of the cam. For the purpose of controlling the movement of the arm as it passes out of the control of the cams w and S the cam S is provided with 105 two inwardly-extending fixed cams 84, between which the heart-shaped ends 82 of the arm 80 pass, thus controlling the movements of the blade as the bowls pass the point of the cam w. It is important that the edge 110 of the folding-blade shall follow as closely as possible the periphery of roll N as the blade advances the fold-line of the sheet, and that on the other hand the blade shall be thrown away from the periphery of roll O as 115 the arm and blade are reversed. For this purpose the arm 80 and the blade t are placed upon the shaft 85 so that the blade is not in a parallel central position to the arm, but forms a slight angle therewith. The arm 80, 120 with its bowls 81 and heart-shaped extensions 82, is also so constructed that a line drawn through the centers of the shaft and bowls will pass to opposite sides of the centers of the projections on the end of the arm, the 125 blade t and the projection 82 on its end of the arm being upon opposite sides of the central line. By the angular position of the blade relatively to the arm and its bowls the edge of the blade is carried inside the central line 130 of the arm as the folding-roll M rotates with the blade in advance, thus enabling the blade-shaft to be placed close to the edge of the roll, so as to carry the blade in a circle of

substantially the same circumference as the roll, its speed thus being the same as that of the paper. The blade also will preferably be curved slightly, the curve being in a direction to throw the edge of the blade inward when in advance relatively to the rotation of the roll M. This curve with the angular position of the blade enables a longer blade to be used, and the curved blade follows more closely the periphery of roll N. By reference to Fig. 12, in which the arm and blade are shown in three positions—viz., as they approach the folding-point, during the operation of folding, and after the arm has been reversed—the operation of this construction will readily be understood. As shown in this figure, the blade *t* during the folding revolution is carried with its edge close to the periphery of the roll M, thus traveling at the same speed as the paper fed by the rolls M N. As the blade reaches the folding-point it will be carried forward by the cam *w* with its edge close to and moving in a circle concentric with the periphery of roll N, the projection 82 engaging the cams 84 and by its shape and position guiding the blade in the same course as it passes out of the control of the cams *w* and S. As the arm passes the point of the cam it will pass into control of the opposite side of the cam *w* and the cam S and a half-revolution of the arm will be completed, the arm then being reversed and the blade being inoperative during the next rotation of the roll M. The shape and position of the projection 82 and the angular position of the blade operate to throw the edge of the blade away from the roll O as the folding movement of the blade is completed and the blade commences its movement away from the rolls N O, this position of the blade being continued by the cam *w* as the arm passes into its control. To aid in this movement, the lower cam 84 is placed at a slightly greater distance from the shaft of roll M than the upper cam. The shaft of roll M, as shown in Fig. 12, is grooved in the plane of rotation of the arm 80 to allow the extension 82 to pass the shaft as the arm is reversed. The blade *t* is adapted to operate either as a guiding or folding blade, and, as a folding-blade, to fold the sheet either on the central line or at one-third or other part of its length from the end. For the purpose of adjusting the roll M and its blade so that the blade shall operate in either of the three ways just referred to the following means are provided: The roll M is driven from the cylinder I by means of a gear 86, which is mounted loosely upon a stud set into the frame, and is held in its outward position in mesh with the gear of roll M by means of a sleeve 88, secured between the gear 86 and the frame by means of a set-screw 89, as shown in Fig. 22. When it is desired to adjust the position of the roll M, the screw 89 will be withdrawn and the sleeve 88 removed from the shaft. The gear 86 may then be moved toward the frame out of mesh with the gear

on roll M, and by similarly loosening the gear 93, by which roll P is driven from roll M, the latter and its blade may be adjusted to any 70 desired position. The roll P is provided likewise with a single-edged folding-blade *x*, the shaft of which is provided with a transverse arm 90, provided with bowls 91 and heart-shaped projections similar to those described 75 in connection with roll M, the blade being operated by an exterior cam T, an interior cam y, and fixed cams 92, the construction and operation of the parts being identical with those of roll M. This roll P is operated 80 from the roll M by means of the intermediate gear 93, which is provided with means similar to those described in connection with the gear 86 whereby the gear may be moved out of mesh for the adjustment of the roll P to bring 85 its folding-blade into either of the positions previously described, the gear 158 on the shaft of roll P being removed or loosened to avoid rotating the slitter, to be described hereinafter. A curved guide 122 is provided, by which the 90 end of the sheet as it passes between the rolls M N, prior to folding, is curved outward, thus permitting it to be more readily folded between the rolls N O, and the sheet is carried from these rolls to roll P by a series of 95 tapes *r*, passing over a guide 79 and between rolls P Q, these tapes forming the upper series of the delivery-tapes. The upper series of tapes *r*, as shown in Fig. 8, pass from a conducting-roll 94 over tightening-pulleys 95, 100 under a conducting-roll to the folding-roll M, thence downward around the roll O over the guide 79, and around the folding-roll Q, returning thence to roll 94. The lower series of tapes *s* pass from the conducting-roll 96 105 around the folding-roll R, thence under a conducting-roll 197, and over tightening-pulleys 198 to the roll 96. If the sheet is not to receive a second longitudinal fold, it passes under the control of tapes *r* from the rolls Q 110 R, between which it is folded by blade *x* on roll P, to the fly 97 at the side of the machine, by which it is delivered against the stops 98 upon the carrier-tapes 99. For the purpose of imparting a second longitudinal fold to 115 the sheet a pair of folding-rolls V extend in the line of motion of the tapes, and above them is mounted in suitable supports in the frame the folding-blade *z*, adapted to fold the sheet between the rolls V, whence the sheet, 120 folded twice longitudinally, passes to the fly 101 at the end of the machine and is delivered on the carrier-tapes 103 against the stops 102. Above the tapes *r* are placed a series 125 of stops 104, carried in brackets upon a shaft 105, extending longitudinally of the machine or transversely to the line of movement of the tapes. These brackets are adjustably secured upon the shaft by set-screws, and the shaft 130 105 may be adjusted by arm 120, Figs. 6 and 7, and held by thumb-screw 121 entering the frame, either so that the stops 104 are in their upper positions, as shown in full lines in Fig. 8, in which case the sheet passes freely be-

neath them to the fly 97, or in their lower position, as shown in dotted lines in the same figure, in which they act to stop the sheets, thus co-operating with the folding-blade z to form the second longitudinal fold. These stops are slotted and adjustable in their brackets in the line of movement of the tapes, being held in position by thumb-screws 123, the stops being thus positioned for sheets of different lengths. The folding-blade z is carried by cranks 106, mounted on shafts 107 in the frame of the machine, the cranks 106 being preferably bell-cranks, as shown, one arm of each being pivotally connected to the blade 15 and their other arms being connected by rod 108, thus insuring certainty in the action of the blade and relieving the strain upon it. One of the cranks 106 is loose upon its shaft 107 and the other is secured to its shaft, which 20 is provided with a crank-arm 109, to which is connected an operating-rod 110, Fig. 7.

A longitudinal folding-blade having a vertical and longitudinal motion and carried by bell-cranks, the other arms of which are connected by a rod, forms no part of the present invention, but is described and claimed in my prior application, Serial No. 160,180, filed March 27, 1885. I have provided, however, an improved mechanism for operating the folding blade positively during its entire movement and for holding the blade out of position when it is not desired to fold the sheet a second time longitudinally.

As shown in Fig. 7, a gear 111 is provided with a crank-pin upon its side, thus forming a crank-wheel, and the arm 110 is provided with a hook and set-screw 112, by which the arm may be secured to a pin upon the frame, thus holding the blade in its upper inoperative position, this position of the arm being shown in full lines in Fig. 7, or by which the arm may be secured to the crank-pin upon the gear 111, as shown in dotted lines in the same figure, thus operating the blade z at each revolution of the gear through crank 109 and shaft 107. To allow the operating-arm to yield in case of a choke, thus preventing breakage, and to give a yielding pressure to the blade, the arm 110 is made in two parts—50 an outer cylinder connected to the crank-arm 109 and a rod 125, sliding therein and carrying the hook 112. A coiled spring 126 is inserted in the cylinder and is attached at one end to a collar 127 on the rod 125, its other 55 end being held against the end of the cylinder. This construction is shown fully in Fig. 23.

In the operation of sheet-folding mechanism it is found that in folding a sheet transversely to a line of previous fold, especially when the sheet consists of many plies, wrinkles are formed in the sheet on both sides of the fold-line at and near the bight of the previous fold of the sheet. I avoid this difficulty by the use of a slitter, which is constructed and arranged to slit the bight of the sheet prior to or during the process of fold-

ing and on the fold-line, the slit extending inward but a short distance—sufficiently to allow the slit edge to open slightly on the 70 fold-line as the fold is made, as shown in Fig. 26.

The slitter and mechanism for operating it may be of any suitable form, it being evident that both may be varied widely. I have provided a simple and convenient construction for this purpose, which is shown particularly in Figs. 3, 7, 8, and 24. Referring to these figures, 147 is a shaft supported in the rear of the folding-blade z in the brackets 148 149. 80 This shaft 147 has adjustably secured thereto arms 150, in which is loosely mounted a shaft 151, carrying the rotary slitter 152. This shaft 151 is provided with a small gear 153, which engages with a gear 154, carried by a 85 sleeve 155, loose on the shaft 147. This sleeve 155 carries also a gear 156, which engages with a gear 157, mounted on a stud in the frame and engaging gear 158, carried by the shaft of roll P, this gear 158 preferably being 90 made removable for a purpose hereinafter explained. The shaft 147 is provided also with a crank-arm 159, preferably adjustable upon the shaft, as shown. To the end of the crank-arm 159 is connected a pitman 160, provided 95 at its end with a hook 161, by which the pitman is secured to the crank-pin 162 on the gear 157. The pitman 160 may be detached from the crank-pin 162 and swung into position to engage with and be secured to pin 163 100 upon the frame, by which the shaft 147 will be rocked to carry the slitter 152 out of position for operation upon the sheet. The operation of the device will readily be understood from the drawings and a brief description. 105

As each sheet passes from the folding-rolls P Q R to a position to be operated upon by the folding-blade z , the rotating slitter 152, by the rocking of the shaft 147 by the crank-wheel 157, will be carried into position to slit 110 the bight of the sheet for a short distance, the further rotation of the crank-wheel 157 rocking the shaft so as to carry the slitter 152 out of position to engage the sheet, the operation being repeated as the next sheet reaches 115 the same point. If the sheet is to be delivered at the side of the machine without the second longitudinal fold, the pitman 160 may be detached from crank-pin 162 and secured to pin 163 upon the frame, when the slitter 152 will 120 be thrown above the plane of movement of the sheet and held in this position, the sheets thus passing onward without being slit. The gear 158 also may be removed to stop the rotation of the slitter. If it be desired to slit 125 the entire sheet without folding, so as to deliver two sheets to fly 97, the gear 158 on the shaft of roll P will first be loosened or removed from the shaft, the gear being secured to the shaft by a set-screw, as shown, or in 130 any other suitable manner. The slitter then may readily be adjusted to the required position by rotating gear 157 and rocking the slitter-carrying arms until the slitter is positioned

to slit the entire sheet during its throw, when the gear 158 will be tightened or replaced on its shaft. In the same way the slitter may be adjusted to slit the edge of the sheet to any extent required. The slit will generally be required only upon one edge of the sheet—that which has received the last fold. When the sheet consists of many plies, however, it may be found desirable to slit the bights at both edges, for which it is evident that the slitter may be readily arranged, the operation of the slitter on one or both edges depending on the relative movements of the sheet-feeding and slitter-rocking mechanism, which may be varied as desired by changing either the gears or form of the connections between gear 157 and pitman 160.

In the operation of cutting, collecting, and folding cylinders as heretofore constructed it has been found that in the process of collecting the under sheet upon the cylinder has a tendency to back up under the tension of the outer sheet or the web as it is received upon the cylinder, this often resulting in the rear edge of the sheet being carried backward over the cutting-groove, so that in the severance of the second sheet a narrow strip is cut from the under sheet, which is objectionable for many reasons. To avoid this objectionable feature I have provided the following mechanism: As shown in Figs. 7, 15, and 16, a shaft 113 is supported in the frame and extends longitudinally of the machine above the cutting and collecting cylinder H, from which cylinder the shaft 113 is driven by means of a gear 114. This shaft 113 carries a tucking-blade 115, supported by arms 128, extending from brackets 129, adjustably mounted upon the shaft 113, and secured in position by means of set-screws, as shown, or in any other suitable manner. The gear 114 is splined to the shaft 113, so that the gear may be moved out of mesh with the gear on cylinder H, and secured in position by a pin 116 in the side of the frame entering a recess in the hub of the gear, thus locking the gear in inoperative position, the sleeve by which the gear is carried being provided with a set-screw, by which it may be secured upon the shaft in any desired position. The pin 116 and recess are so placed that when the pin enters the recess the shaft 113 will have been rotated so that the tucking-blade 115 is carried out of engagement with the cylinder H, and is then held in this position by the locking of gear 114, the blade being in operative position only when the sheets are to be collected. As shown clearly in Fig. 15, the gear 114 and the tucking-blade are so timed in their movement relatively to the cylinder H that the blade 115 enters a groove 117, formed in the latter cylinder just in advance of the cutting-groove, thus operating to tuck and hold temporarily within the groove the rear end of the sheet, drawing the sheet away from the cutting-groove and carrying its end down into the groove 117. It may happen that as the blade 115 is drawn

from the groove 117 by the movement of the cylinders the end of the sheet will be drawn or will fly out of the groove 117, the end thus being carried back over the cutting-groove. To prevent this I preferably provide the groove 117 with a shoulder 9, which extends over the rear side of the groove, and against which the end of the sheet is held, thus preventing its passing out of the groove. I provide, also, a series of guards 118, formed, preferably, of wire or narrow strips of sheet metal curved around the cylinder H, and extending forward nearly to the point at which the web passes between the cylinders H I, these guards acting to hold the collected sheets to the surface of the cylinder as the tucking-blade is withdrawn and to prevent buckling of the sheet between the groove 117 and the end of the guards, all slack in the paper thereby being transmitted beneath the guards to the groove 117 and taken up as the end of the sheet is tucked into the groove, as previously described. It will be understood that the blade 115 is recessed opposite the guards 118 to permit the blade to enter the groove. The guards 118 are carried by supports 119, adjustably mounted upon a shaft 130 and held in position thereon by thumb-screws 131, these supports carrying also guards 132, extending about the cylinder H in a direction opposite to that of the guards 118.

In the operation of web-printing machines in which the paper, as is usual, is led to cutting, collecting, and folding cylinders, one of which carries a set of sheet-holding pins, by which the sheet is seized and carried about the cylinder, it is found that occasionally, after the web has been seized by the pins as it passes between the cylinders, it will be removed therefrom, thereby interfering with the operation of the machine by causing a choke or otherwise. This occurs in some cases independently of any special manner in which the web is led from the folder to the collecting-cylinders. In machines, however, in which a longitudinal folder of the form shown is employed it is found that the best results are obtained when the folder is so positioned that the web does not pass from the folder to the feeding-rolls in a direct vertical line, but, as shown in Fig. 17, at a small angle to the vertical, the web moving slightly toward the front end of the feeding-rolls. With this arrangement of the folder it is found that a slight slack will occur in the rear edge of the web as it passes from the feeding-rolls 52 to the cutting and collecting cylinders, on account of the return of the web to a vertical movement by the action of the cylinders, and this slack causes an increase in the tendency of the web to be thrown off the pins when the leading edge of the web has passed between the cutting and folding cylinders. For the purpose of avoiding this and for the purpose of taking up the slack resulting from the position of the folder I have provided the following mechanism:

Referring to Figs. 15 to 20, a shaft 133 is supported in the frame of the machine by a bracket 134 and carries a deflecting-guide W, formed, preferably, from a sheet of thin 5 spring metal bent at its lower end, by which it engages the web, as shown in Figs. 15 and 20, or otherwise formed so as to prevent a sharp edge being brought in contact with the web. This shaft 133 extends longitudinally of the 10 machine between the feeding-rolls 52 and the cutting and folding cylinders H I, and is preferably unsupported at its rear end, its front end being adjustably supported in the bracket 134 by the means shown fully in Fig. 17, in 15 which the shaft 133 is adjustably secured in a sleeve 135 by means of the thumb-screw 146, this sleeve carrying a pin 136, which enters an opening in a horizontal arm of the bracket 134 and is adjustably secured therein 20 by means of a thumb-screw 137. By this means the shaft 133 may be swung horizontally to any desired position, the shaft thus being placed at an angle to the web, for a purpose presently to be described. The blade 25 W is carried by a sleeve 138 upon the shaft 133, which sleeve is loosely mounted upon the shaft and provided with a slot 139, the ends of which engage with a pin 140 upon the shaft to limit the movement of the sleeve 30 and blade thereon. Upon the shaft 133 is coiled a spring 141, one end of which is secured to the sleeve 138 and the other end to a collar 142, adjustably secured upon the shaft 133 by means of a set-screw 144. It is 35 evident that by this construction the spring 141 may be adjusted so as to press the blade W against the web E with any desired pressure, this pressure being adjustable also by the connection between the shaft 133 and 40 sleeve 135. In place of the adjustable shaft 133, by which the blade W can be placed at an angle to the web, the shaft 133 may be rigidly supported in the bracket 134 and the blade W be constructed as shown in Fig. 45 19, being of a triangular form, so as to press slightly, or not at all, at the front edge of the web, but extending downward from the shaft at the rear edge of the web, so as to press sufficiently thereon for the required tension. 50 In some cases it may be found that a tension on only a narrow strip of the rear side of the web will be required. In this construction the shaft 133 may be supported at its rear end also in a bracket 145, secured to the 55 frame of the machine. The sleeve 138, carrying the blade W, may be secured directly to the shaft 133, and the blade W be constructed of sufficient elasticity, so as to give the required tension without the use of the 60 spring 141, the sleeve and blade being then adjusted only by the rotation of the shaft 133 in the supporting-bracket, being secured in the desired position by means of the screw 146, as shown in Fig. 19. The operation of 65 this device is as follows: As the web is led from the folder in the direction shown in Fig. 17 and passes from the rolls 52 to the cylinder

H I the tension of the cylinders H I upon the web E tends to return the web to a movement in a direct vertical line, and this will 70 cause a slight slack at the rear edge of the web. The blade W of Fig. 17 will then be adjusted by the horizontal rotation of the supporting-pin 136 in the bracket 134 to a position in which the pressure of the blade W 75 upon the web E and its angular position relative thereto will be just sufficient to take up the slack at the rear edge and to deflect the web slightly, so as to cause an upward tension thereon, which will operate to draw the leading edge of the web against the cylinder H, thus forcing the edge of the web inward to the base of the pins and preventing its being thrown off the same. Independently of the angular movement of the shaft 133 the deflecting-guide W may be adjusted to the required tension by the adjustment of the shaft 133 in sleeve 135 or by that of spring 141, as previously described. The operation of the construction shown in Fig. 19 is the same, except 80 that the blade and shaft are placed parallel with the web widthwise, and the excess of tension at the rear edge of the web is produced by the greater width of the deflecting-guide at that point. 85

It is obvious that the deflecting-guide W, by which a tension upon the web is produced tending to draw it down to the base of the sheet-holding pins, may be employed independently of the means devised for adjusting 90 or forming the same, so as to take up the slack in the rear edge of the web, and such a deflecting-guide, independently of the special direction in which the web is led, forms a part 95 of my invention. 100

It will be understood that all the mechanism described is driven by suitable trains of gearing from the power-shaft 123 at the delivery end of the machine. This gearing is shown in the drawings, but need not be described herein. 110

The general operation of the machine in connection with the various products will now be described, it being understood that the number and arrangement of the forms on the type-cylinder A will be varied in accordance 115 with the use of the press as a newspaper or pamphlet press, and that the additional transverse and longitudinal folds imparted to the sheet after passing the cutting and collecting cylinders may be for the production of a newspaper folded in smaller compass or of a product of a larger number of pages. 120

For a product having one longitudinal and one transverse fold, or an eight-page product, 125 the collecting mechanism of cylinder H will be thrown out of operation, the plate L being positioned so that the blade k will be operated to fold the sheet at each revolution of the cylinder and the pins c similarly retracted, 130 and the folding-rolls M and P will be adjusted out of folding position, but so that the blades t and x will guide the leading edge of the sheet between their respective rolls, all as described

above, and the sheet, folded once longitudinally and once transversely, will pass from the last pair of rolls under control of the tapes $r s$ and be deposited upon the fly 97 and carrier-tapes 99 at the side of the machine, the blade z and the stops 104 being in inoperative position.

For a product folded once longitudinally and twice transversely, or a sixteen-page product, the adjustment will be the same as for the eight-page product, except that one of the folding-rolls M P will be adjusted to fold the sheet received from the cylinder H upon its central line. In this case the sheet, folded once longitudinally and once transversely by the longitudinal folder and cutting and collecting cylinders, will receive an additional transverse fold from the folding-blade of the roll M or P, and thence pass, as before, to the fly 97 and carrier-tapes 99 at the side of the machine.

For a product having one longitudinal and three transverse folds, or a thirty-two-page product, the adjustment will be the same as in the case of a sixteen-page product; but both cylinders M P will be adjusted to fold the sheet received by them upon its central line. In this case the sheet, folded once longitudinally and once transversely by the longitudinal folder and the cutting and collecting cylinders, will receive two transverse folds from the folding-blades $t z$ of the rolls M P and will pass from the cylinder P to the fly 97 and carrier-tapes 99 at the side of the machine, as before.

For a product having the three longitudinal transverse folds and an additional longitudinal fold, or a sixty-four-page product, the adjustment of all the folding-cylinders will be the same as in the case of the thirty-two-page product; but the folding-blade z will be brought into operative position by the connection of the arm 110 with the gear or crank wheel 111, as previously described, and the stops 104 will be thrown downward into position to stop the sheet as it passes forward under control of the tapes $r s$. The blade z will then operate to fold the sheet longitudinally between the rolls V, whence, folded once longitudinally and three times transversely and with an additional longitudinal fold from the folding-blade z , the sheet will pass to the flies 101 and tapes 103 at the end of the machine.

In all the products above described the blades $t z$ have been adjusted either to guide the leading edge or to fold on the central line of the sheet, the product of an additional fold being in each case of double the number of pages of the preceding product.

For the twenty-four-page product shown in Fig. 25 the cylinder H will be adjusted as described in connection with the preceding products—that is, to fold at each revolution of the cylinder. The folding-roll M, however, will be adjusted so that its blade will fold the sheet received from the cylinder H, not upon its central line, but on a line one-third of the

length of the sheet from the leading edge thereof, this roll thereby transmitting the sheet through the rolls N O to the roll P with one additional transverse fold of one-third. The roll P will be adjusted to fold the sheet thus received from cylinder N so as to form another fold of one-third the length of the sheet as it left the cutting and collecting cylinders, thus completing a product consisting of twenty-four pages. The sheet, folded thus once longitudinally and three times transversely, passes under control of the tapes to the fly 97 and tapes 99 at the side of the machine.

For a product of forty-eight pages the cylinder H and rolls M and P will be adjusted as in the case of the twenty-four-page product; but the longitudinal folder will be brought into operative position and an additional longitudinal fold imparted to the sheet, thus forming forty-eight pages.

It will be understood that by the operation of the plate L through the gears 68 69 and shaft 90, as previously described, the cylinder H may be adjusted to collect the sheets as they pass from the longitudinal folder F, any of the products above described thereby being doubled, so that the machine is capacitated for products consisting of two sheets folded once longitudinally and either once, twice, or three times transversely, with or without an additional longitudinal fold, and the highest-paged product of the machine is one consisting of two sheets of sixty-four pages each, or a completed product of one hundred and twenty-eight pages.

While the products above described are the main products of the machine, it will be evident to one skilled in the art that many other variations in product may readily be made and that the products described may be produced by other adjustments. Thus, if a four-page product be desired, a web of half-width may be used, thus printing and perfecting four pages, the web in this case not being folded by the longitudinal folder E, but passing over the side of the same to the cutting, collecting, and folding cylinders H I, by which the sheet is severed and folded once transversely, and passing thence without additional fold to the carrier-tapes 99 at the side of the machine. The second longitudinal fold may be imparted to products having either one or two transverse folds, if desired, thus varying further the form of the products. If a small pamphlet of a large number of pages be desired, it is evident that either by the addition of a cutting mechanism to this machine or, preferably, by an independent cutting-machine the sheets as received from the longitudinal folder z and rolls V may be severed transversely, two or more products of ninety-six or one hundred and twenty-eight pages each thus being formed, this depending on the size of the machine and upon the position of the forms upon the type-cylinder. The slitter 42 may be thrown into operative posi-

tion when desired, two sheets being thus transmitted to the folder, and a pasting mechanism may be added to lay a line of paste along the side edge or central line of the sheet. Other attachments common in web-printing machines will readily suggest themselves as adapted for use with this machine. They are omitted herein in order to permit a clearer illustration of the special features constituting the present invention.

It will be understood that a printing mechanism of any suitable form may be used in connection with the delivery mechanism of this machine, and that the specific improvements in feeding, cutting, collecting, and folding mechanism above described, and which will be claimed hereinafter, are of general application in such mechanism.

What I claim is—

1. The combination, with feeding mechanism, of a pair of feeding-rolls to which the sheet passes from the feeding mechanism, one of said rolls being provided with a folding-blade adapted to act also as a guiding-blade, and means for adjusting the position of the blade relatively to the feeding mechanism, whereby the blade may be operated to guide the leading edge of the sheet or to fold the sheet, substantially as described.
2. The combination, with feeding mechanism, of a pair of feeding-rolls to which the sheet passes from the feeding mechanism, one of said rolls being provided with a folding-blade, and means for adjusting the position of the blade relatively to the feeding mechanism to vary its line of action on the sheet, substantially as described.

3. The combination of a roll provided with a folding-blade adapted to act also as a guiding-blade, a pair of feeding and folding rolls receiving the sheet from the folding-blade, and means for adjusting the position of the folding-blade relatively to the leading edge of the sheet, so as to either guide the leading edge of the sheet or fold the sheet between the feeding and folding rolls, substantially as described.

4. The combination of a roll provided with a folding-blade, a pair of feeding and folding rolls receiving the sheet from the folding-blade, and means for adjusting the position of the folding-blade relatively to the leading edge of the sheet to vary its line of action on the sheet, substantially as described.

5. A folding mechanism consisting of three rolls coacting to form two pairs of feeding-rolls, a folding-blade carried by one of said rolls and adapted to act also as a guiding-blade, and means for adjusting the position of the folding-blade relatively to the leading edge of the sheet, so as to either guide the leading edge of the sheet or fold the sheet between the other two rolls, substantially as described.

6. A folding mechanism consisting of three rolls coacting to form two pairs of feeding-

rolls, a folding-blade carried by one of said rolls, and means for adjusting the position of the folding-blade relatively to the leading edge of the sheet to vary its line of action on the sheet, substantially as described.

7. The combination, with folding mechanism, of a pair of feeding-rolls to which the sheet passes from the folding mechanism, one of said rolls being provided with a folding-blade, and detachable driving connections permitting the blade-roll to be rotated independently of the feeding mechanism to adjust the blade to different positions relatively to the latter, whereby the blade may be operated to act upon different lines of the sheet, substantially as described.

8. A folding mechanism consisting of a plurality of groups of three rolls, each coacting to form two pairs of folding-rolls, one roll of each group being provided with a folding-blade, means for adjusting the position of each folding-blade relatively to the leading edge of the sheet, so as to either guide the leading edge of the sheet or fold the sheet between the other rolls of its group, and means for feeding the sheet from each group to the next, substantially as described.

9. The combination of a plurality of combined sheet feeding and transverse folding mechanisms acting upon the sheet successively and adapted to feed either with or without folding, and means for adjusting any or all of the sheet feeding and folding mechanisms to vary the fold-lines or to cause them to feed the sheet without folding, substantially as described.

10. The combination of a plurality of combined sheet feeding and transverse folding mechanisms acting upon the sheet successively, and means for adjusting any or all of the sheet feeding and folding mechanisms to vary the fold-lines, substantially as described.

11. In a web-printing machine, the combination, with the main sheet cutting and folding mechanism, of a plurality of combined sheet feeding and transverse folding mechanisms acting upon the sheet successively, means for adjusting any or all of the sheet feeding and folding mechanisms to feed the sheet with or without folding, the path of the sheet between the mechanisms remaining the same, and a longitudinally-folding mechanism adapted to act upon the sheet after it leaves the sheet feeding and transverse folding mechanisms or to be thrown out of operation, substantially as described.

12. The combination, with a pair of folding-rolls, of roll M and its folding-blade having an operating-arm upon its shaft, cams for actuating said blade to follow the surface of one of the folding-rolls till the fold is made, said cams commencing and completing the partial revolution of the blade, and independent cams acting upon said arm to control the blade during the intermediate part of its movement and operating to throw the blade

away from the surface of the other folding-roll as the fold is completed and the blade reversed, substantially as described.

13. The combination, with a pair of folding-rolls, of roll M and its curved folding-blade having an operating-arm upon its shaft, cams for actuating said blade to follow the surface of one of the folding-rolls till the fold is made, said cams commencing and completing the 10 partial revolution of the blade, and independent cams acting upon said arm to control the blade during the intermediate part of its movement and operating to throw the blade away from the surface of the other folding-roll as the fold is completed and the blade reversed, substantially as described.

14. The combination, with roll M and its blade having a transverse operating-arm on its shaft, provided with bowls 81 and extensions 82, the extensions being placed out of 20 central position relatively to the bowls and shaft, of cams acting upon said bowls for commencing and completing the partial revolution of the blade, and independent cams 25 acting on said extensions for controlling the blade during the intermediate part of its partial revolution, substantially as described.

15. The combination, with roll M and its blade having a transverse operating-arm on 30 its shaft, provided with bowls 81 and extensions 82, the extensions at the opposite ends of the arm being placed on opposite sides of a line central to the shaft and bowls, of cams acting upon said bowls for commencing and 35 completing the partial revolution of the blade, and independent cams acting on said extensions for controlling the blade during the intermediate part of its partial revolution, substantially as described.

16. The combination, with a pair of folding-rolls, as N O, of roll M, forming, with one of the folding-rolls, a pair of feed-rolls, a folding-blade carried by roll M and having an operating-arm upon its shaft, fixed cams for 45 commencing and completing the partial revolution of the blade, and independent cams acting upon said arm to control the blade during the intermediate part of its partial revolution, substantially as described.

17. The combination, with a pair of feeding-rolls, as N O, of roll M, carrying a folding-blade and coacting with roll N to form a pair of feeding-rolls, a feeding mechanism for advancing the sheets to rolls M N, and removable gear 86, by which roll M is driven, said 55 roll M being free to rotate independently of the feeding mechanism when gear 86 is removed, whereby the position of the blade relatively to the feeding mechanism may be adjusted, substantially as described.

18. In a web-printing machine, the combination, with the delivering mechanism, of a movable frame carrying the longitudinal folder, feeding mechanism mounted on the 65 frame for advancing the web to the folder,

and means for adjusting the frame longitudinally of the web, substantially as described.

19. In a web-printing machine, the combination, with the delivering mechanism, of a movable frame carrying the longitudinal folder, conducting-rolls mounted on the frame, conveying-tapes extending from the main frame and passing around said conducting-rolls, and means for adjusting the movable frame longitudinally of the web, substantially 75 as described.

20. In a web-printing machine, the combination, with the delivering mechanism, of a movable frame carrying the longitudinal folder, conducting-rolls mounted on the frame, 80 conveying-tapes extending from the main frame and passing around said conducting-rolls, mechanism for driving said conducting-rolls from the main driving-shaft, and means for adjusting the movable frame longitudinally 85 of the web, substantially as described.

21. The combination, with frame G, adjustable on the main frame and carrying gear 3, and mechanism driven from said gear, of driving-gear 7, mounted in the main frame, 90 and an intermediate 4, connecting gears 3 and 7 and mounted in arms swinging from the shafts of said gears, substantially as described.

22. The combination, with frame G, adjustable on the main frame and carrying gear 3, 95 and mechanism driven from said gear, of driving-gear 7, mounted in the main frame, an intermediate 4, connecting gears 3 and 7 and mounted in arms swinging from the shafts of said gears, and slotted plate h on 100 frame G, receiving the shaft of gear 4, substantially as described.

23. The combination, with frame G, adjustable on the main frame and carrying gear 3, and mechanism driven from said gear, of 105 driving-gear 7, mounted in the main frame, an intermediate 4, connecting gears 3 and 7 and mounted in arms swinging from the shafts of said gears, and slotted plate h, adjustable on frame G and receiving the shaft 110 of gear 4, substantially as described.

24. The combination, with a cutting and collecting cylinder provided with a groove in front of the cutting-line, of means for tucking the rear edge of the under sheet or sheets into 115 the groove, substantially as described.

25. The combination, with a cutting and collecting cylinder provided with a groove in front of the cutting-line, of a blade operating to tuck the rear edge of the under sheet or 120 sheets into the groove, substantially as described.

26. The combination, with a cutting and collecting cylinder provided with a groove in front of the cutting-line, of a revolving blade 125 operating to tuck the rear edge of the under sheet or sheets into the groove, substantially as described.

27. The combination, with a cutting and collecting cylinder provided with a groove in 130

front of the cutting-blade, of a blade operating to tuck the rear edge of the under sheet or sheets into the groove, and means for throwing the blade in and out of operation, substantially as described.

28. The combination, with a cutting and collecting cylinder provided with a groove in front of the cutting-line and a shoulder extending over the rear side of the groove, of a blade operating to tuck the rear edge of the under sheet or sheets into the groove, substantially as described.

29. The combination, with a cutting and collecting cylinder provided with a groove in front of the cutting-line, of a blade operating to tuck the rear edge of the under sheet or sheets into the groove, and guards extending forward around the cylinder from the tucking-point, substantially as described.

30. In a web-printing machine, the combination, with the cutting and folding cylinders and their sheet-retaining devices, of a deflecting-guide for the web in the rear of the cutting and folding cylinders, substantially as described.

31. In a web-printing machine, the combination, with the cutting and folding cylinders and their sheet-retaining devices, of a yielding deflecting-guide for the web in the rear of the cutting and folding cylinders, substantially as described.

32. In a web-printing machine, the combination, with the longitudinal folder and the cutting and folding cylinders and their sheet-retaining devices, of a deflecting-guide placed between the folder and cylinders and constructed and arranged to deflect the inner edge of the web sufficiently to take up the slack caused by the lead of the web, substantially as described.

33. In a web-printing machine, the combination, with the longitudinal folder and the cutting and folding cylinders and the sheet-retaining devices, of a deflecting-guide placed between the folder and cylinders, the guide extending widthwise of the web and constructed and arranged to deflect the inner edge of the web at a greater angle than the outer edge, whereby the slack caused by the lead of the web is taken up, substantially as described.

34. In a web-printing machine, the combination, with the longitudinal folder and the cutting and folding cylinders and their sheet-retaining devices, of a deflecting-guide placed between the folder and cylinders, the guide extending widthwise of the web and supported to swing in a plane transverse to the web, whereby the guide may be adjusted to take up the slack caused by the lead of the web, substantially as described.

35. In a web-printing machine, the combination, with the longitudinal folder and the cutting and folding cylinders and their sheet-retaining devices, of a deflecting-guide placed between the folder and cylinders, the guide

extending widthwise of the web and at an angle to the line of normal movement of the web, whereby the inner edge of the web is deflected sufficiently to take up the slack caused by the lead of the web, substantially as described.

36. The combination, with a folding mechanism adapted to fold a sheet transversely to a line of previous fold, of a movable slitter and mechanism for actuating said slitter to slit the bight of the previous fold on the fold-line of the folding mechanism and prior to or in the process of folding, substantially as described.

37. The combination, with a folding mechanism adapted to fold a sheet transversely to a line of previous fold, of a slitter operating to slit the bight of the previous fold on the fold-line of the folding mechanism and prior to or in the process of folding, and means for moving said slitter longitudinally of the sheet during the slitting operation, substantially as described.

38. The combination, with a folding mechanism adapted to fold a sheet transversely to a line of previous fold, of a slitter operating to slit the bight of the previous fold on the fold-line of the folding mechanism and prior to or in the process of folding, said slitter being adjustable to vary the length of the slit, substantially as described.

39. The combination of a folding mechanism adapted to fold a sheet transversely to the line of previous fold, a slitter operating to slit the bight of the previous fold on the fold-line of the folding mechanism and prior to or in the process of folding, means for adjusting the slitter for varying the length of the slit, and means for throwing the slitter out of operation, substantially as described.

40. The combination, with a folding mechanism adapted to fold a sheet transversely to a line of previous fold, of a rotary slitter and means for reciprocating said slitter to slit the bight of the previous fold on the fold-line of the folding mechanism and prior to or in the process of folding, substantially as described.

41. The combination, with blade *z*, cranks 106, shafts 107, and crank-arm 109, of crank-wheel 111 and pitman 110, connecting the crank wheel and arm, substantially as described.

42. The combination, with blade *z*, bell-cranks 106, rod 108, shafts 107, and crank-arm 109, of crank-wheel 111 and pitman 110, connecting the crank wheel and arm, substantially as described.

43. The combination, with blade *z*, cranks 106, shafts 107, and crank-arm 109, of crank-wheel 111, pitman 110, and means for securing the pitman to either the crank-wheel or frame for operating the blade or carrying and holding it out of operative position, substantially as described.

44. The combination, with shaft 67 and re-

movable gear 68, of plate 74 for securing the gear to the shaft, gear 69, engaging gear 68, pin 72 for locking gear 69 to the frame, and sliding safety-plate 77, substantially as described.

45. The combination, with the cylinder H, its shaft 67, removable gear 68, and plate 74 for securing the gear to the shaft, of the movable cam-plate L, gear 69, engaging gear 68 and operating the cam-plate, pin 72 for locking gear 69 and the plate against movement, and sliding safety-plate 77, substantially as described.

46. The combination, with shaft 67 and removable gear 68, of plate 74, secured to the

gear, and bolt 75 for securing the plate to the shaft, the plate being provided with an enlarged screw-threaded opening through which the bolt passes, the opening being adapted to receive a larger bolt for removing the gear by pressure against the end of the shaft, substantially as described.

In testimony whereof I have hereunto set my hand in the presence of two subscribing witnesses.

LUTHER C. CROWELL.
